UNITED STATES PATENT OFFICE.

VICTOR E. EDWARDS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

TRAVELING CRANE.

SPECIFICATION forming part of Letters Patent No. 761,154, dated May 31, 1904

Application filed February 6, 1902. Serial No. 92,786. (No model.)

To all whom it may concern:

Be it known that I, VICTOR E. EDWARDS, a citizen of the United States, residing at Worcester, in the county of Worcester and 5 Commonwealth of Massachusetts, have invented a new and useful Improvement in Traveling Cranes, of which the following is a specification, accompanied by drawings forming a part of the same, in which—

10 Figure 1 represents a plan view of a traveling crane embodying my invention. Fig. 2 is a side elevation of one of the central sections of the crane. Fig. 3 is a plan view of the same. Fig. 4 is a plan view of a pair of 15 the lifting-fingers and their connected actuating mechanism. Fig. 5 is a side view of a series of lifting-fingers with their connected actuating mechanism. Fig. 6 represents a side view of a pair of the posts forming the 20 divisions between pockets to receive rods or bars. Fig. 7 is an edge view of one of the posts. Fig. 8 is an enlarged view of one of the rotating heads carrying the lifting-fingers. Fig. 9 is a plan view of one pair of lifting- 25 fingers with a section of bar supported thereon. Figs. 10 and 11 are side and top views, respectively, of one of the hinged joints of the framework connecting the traveling carriers; and Fig. 12 is a plan view of a portion of the 30 lifting-frame.

Similar reference letters refer to similar parts in the different views.

My invention relates to certain improvements in a traveling crane; and it consists in 35 the construction and arrangement of parts as hereinafter described, and pointed out in the annexed claims.

In the accompanying drawings I have represented one of my improved traveling cranes 40 in connection with a conveyer arranged to conduct metal rods or bars into position to be lifted by the crane and with a series of pockets into which the rods are delivered, and my improved crane is especially adapted to the 45 purpose of lifting and transferring long rods or bars, which in my improved crane are supported upon and lifted by rotating fingers

provided with laterally-projecting tips arranged to be carried beneath a rod or bar to be lifted by the rotation of the fingers, although other known forms of grappling mechanism for engaging the article to be lifted may be employed.

My improved traveling crane comprises a fixed elevated framework supported upon 50 posts A A and provided with transverse tracks B, upon which travel the carriers C, each of which is moved along its track B by a driving-cable C', having its ends connected to an arm C², projecting from the carrier C. The carriers C are suspended beneath the tracks B and are supported thereon by rolls C³. The movement of the carriers C along the tracks B is accomplished by winding the driving-cables C' around grooved drums D, attached to 55 a driving-shaft D', which is rotated by a motor E through the intermediate gears E' E² E³ E⁴ and intermediate shaft E⁵. The transverse tracks B are arranged at intervals along the elevated framework, and each of said tracks 60 supports a carrier-frame C, suspended beneath the tracks B, each of the carriers being provided with its own driving-cable C' and grooved drum D, attached to the main driving-shaft D'. The ends of the driving-cables C' are provided with screw-threaded 65 eyebolts C⁴, which pass through the arms C² and are provided with nuts C⁵, by which the driving-cable is tightened, and the position of the carrier-frames C is adjusted to 70 bring the several frames into alignment. The driving-shaft D' is rotated in one direction to move the carrier-frames C in one direction, and it is reversed to move the carriers C in the opposite direction, and the shaft D is of sufficient size to resist the torsional strain incident to the movement of the carriers C in order to cause the several carriers to maintain 75 their alignment during their movement along the transverse tracks B. The suspended carrier-frames C are united at their lower ends by longitudinal bars C⁶, upon which are mounted a motor-cylinder F^a and a series of rolls F'. The cylinder F^a is provided with a pis-

ton F² and a piston-rod F³, extending through the opposite ends of the cylinder and connected with parallel bars F⁴, to which a series of chains F⁵ are attached by pins F⁶.
 5 The chains F⁵ pass over the rolls F⁷, and their opposite ends are attached to a longitudinal lifting-frame G, capable of a rising-and-falling movement between guides G⁸ and G⁹. (Shown on a larger scale in Fig. 4.) The lifting-frame G supports a series of rotating lifting-fingers H and their actuating mechanism, consisting of a motor-cylinder I, enclosing a piston I' and having its piston-rod I² pivotally connected by links I³ with levers
 10 J, which are pivoted at one end at J' and are connected at their free ends with cables J², having their opposite ends connected to spiral springs J³, attached to the fixed framework. Attached at intervals to the cables J² are col-
 15 lars J⁴, provided with trunnions J⁵, journaled in the bifurcated ends of arms J⁶, which are attached to spindles J⁷, journaled in arms J⁸, rigidly attached to the framework G. The rotating spindles J⁷ are capable of a slight
 20 longitudinal movement in their journal-bear-
 ings, and they carry at their lower ends heads J⁹, provided with a groove J¹⁰, undercut on one side, as at J¹¹, to receive a horizontal bar H', which carries at its opposite ends the fin-
 25 gers H, bent vertically downward from the ends of the bar H', with the sections a of the fingers substantially parallel with their axis of rotation and far enough apart to receive between them the bar or rod to be lifted. At
 30 the ends of the sections a the fingers are ex-
 tended laterally and obliquely downward, forming the tips a', with their ends separated to allow them as the fingers are lowered to pass downward upon opposite sides of the bar
 35 or rod to be lifted and by the rotation of the spindle J⁷ be carried beneath the bar or rod, so that the upward movement of the fingers will lift the rod. The horizontal bar H' is held against the undercut side of the groove
 40 by means of set-screws H², thereby allowing the fingers to be removed from the heads J⁹.
 Each of the transverse tracks B is provided with a stop-plate, one of which is shown at K, Fig. 3, by which the movement of the car-
 45 riers C is limited in one direction, thereby determining the position of the carriers at one end of their travel or the position in which they are to pick up the rod or bar. The rod or bar to be lifted is brought into
 50 position to be engaged by the rotating fingers H by means of a series of rotating conveyer-rolls L, journaled in a frame L' and driven by a series of miter-gears from a connecting-shaft L². Each of the rolls L is preferably
 55 provided at its opposite ends with projecting flanges L³, which serve to position the rod or bar laterally to be engaged by the fingers H. When a rod or bar M has been placed in position on the conveyer-rolls L and beneath the
 60 carrier-frames C, the lifting-frame G is low-
 65

ered by moving the parallel bars F⁴ in the direction of the arrow 1, Fig. 5, thereby causing the fingers H to straddle the rod or bar held on the conveyer-rolls L. The finger-spindles J⁷ are then rotated about one-quarter 70 revolution in order to swing the laterally-projecting tips a' into the position shown at a', Fig. 4, thereby carrying the tips a' beneath the bar supported on the conveyer-rolls L, so that when the fingers are again lifted 75 by raising the lifting-frame G the bar will lie across the tips of the fingers in the position represented at M, Fig. 9, and be raised by the fingers. The traveling carrier-frames C are then moved along the transverse tracks 80 B, carrying the suspended bar M over any one of a series of pockets N, into which it may be delivered by reversing the rotation of the fingers H. The pockets N are formed by a series of upright posts N', having their upper 85 ends connected by an angle-plate N², placed upon the tops of the posts with its apex up-
 90 permost. Each of the posts N' consists at its lower end of a pair of bars O O', which are curved in opposite directions and attached to a horizontal beam P, so that each of the posts is braced against lateral displacement in both directions by the oppositely-curved bars O O'.
 The traveling cranes C are connected at 95 their lower ends by a framework C⁶, and pro-
 vision is made for the deflection of the bars comprising the connecting-framework caused by the heat radiated from the heated rods or bars to be lifted by making the connecting-framework C⁶ in sections and hinging the 100 ends of the same to each other and to the carrier-frames C. This is accomplished, as shown in Figs. 10 and 11, by forming over-
 105 lapping lugs C⁷ on the ends of the frames C⁶ and hinging the overlapping lugs upon a pin C⁸, extending transversely to the carrier-frame C, so that an unequal expansion of the frame-
 110 work will cause the sections of the frame to turn slightly upon the pivots C⁸. The lifting-bars G, upon which the rotating fingers H 110 are supported, are also made in sections, with the ends of each section connected by screw-
 threaded bolts G² through the ends of the lifting-bars G⁷, connected to the chains F⁵.
 What I claim as my invention, and desire 115 to secure by Letters Patent, is—
 1. In a traveling crane, the combination of an overhead track, a rigid depending frame provided with rolls at its upper end adapted to move on said track, means for moving said frame along the track, a lifting mechanism consisting of a rigid frame, capable of vertical movement in said rigid depending frame, a rotating spindle in said vertically-moving frame and fingers carried by said spindle 120 adapted to engage the article to be lifted, substantially as described.
 2. In a traveling crane, the combination of a series of parallel overhead tracks, a series of rigid depending frames each provided with 125

rolls adapted to run on said tracks, rigid connecting-bars by which the lower ends of said depending frames are united and means for moving said frames along said tracks, substantially as described.

3. The combination with a series of parallel overhead tracks and rolls running thereon, depending frames suspended from said rolls, means for connecting the lower ends of said frames and means for moving said frames individually along said tracks, substantially as described.

4. The combination with a series of parallel overhead tracks, rolls running on said tracks, depending frames suspended from said rolls, means for connecting the lower ends of said frames, means for moving said frames along said tracks and a lifting mechanism carried by the said connecting-frames, substantially as described.

5. The combination of a series of parallel overhead tracks, rigid depending frames supported by said tracks and capable of moving thereon, a rotating shaft, drums carried on said shaft corresponding to said frames, driving-cables attached at their ends to each of said frames and wound about said drums, whereby the rotation of said shaft will move said frames simultaneously along said ways, substantially as described.

6. The combination of a series of parallel overhead tracks, rolls adapted to run on said tracks, rigid depending frames suspended from said rolls, rigid bars uniting the lower ends of said depending frames, a lifting mechanism carried by said depending frames, a common driving-shaft and connecting operative mechanism between said shaft and said depending frames, whereby they are simultaneously moved along said tracks, substantially as described.

7. The combination with a series of overhead tracks, of a series of rigid frames adapted to be moved along said tracks, a frame for rigidly uniting said frames at their lower ends, whereby they are held from swaying sidewise, a lifting mechanism supported by said uniting-frame, and means for simultaneously moving the frames along said tracks, substantially as described.

8. The combination with a series of parallel overhead tracks, traveling frames arranged to be moved along said tracks, an actuating mechanism whereby said frames are simultaneously moved along said tracks, a framework for connecting the lower ends of said frames together and a lifting mechanism supported by said connecting-framework, substantially as described.

9. The combination in a traveling crane with a series of tracks of a series of moving carrier-frames supported by, and dependent from said tracks, means for moving said carrier-frames simultaneously along said tracks, and a connecting-framework uniting said car-

rier-frames and pivotally connected thereto in order to provide for the deflection caused by unequal heating, substantially as described.

10. In a traveling crane, the combination with a series of parallel overhead tracks, of a series of rigid carrier-frames moving thereon, jointed connecting-framework between said carrier-frames, a lifting mechanism supported on said framework and comprising a series of lifting devices for engaging the article to be lifted and a common actuating-motor, substantially as described.

11. The combination with a series of traveling carrier-frames, of a connecting-framework between said frames, a lifting mechanism supported by said framework and comprising a rising-and-falling frame and vertical guides for said rising-and-falling frame, substantially as described.

12. The combination of a series of parallel overhead tracks and a series of carrier-frames moving thereon, of actuating mechanism for simultaneously moving said frames, a connecting-framework between said carrier-frames, vertical guides supported by said connecting-framework, a vertically-moving frame between said guides and a series of lifting devices carried by said vertically-moving frame, substantially as described.

13. In a crane, the combination with a traveling carrier-frame, of a lifting mechanism comprising a rotating spindle and a pair of bent fingers carried by said spindle, whereby said fingers are simultaneously carried beneath the article to be lifted by the rotation of said spindle, substantially as described.

14. The combination in a crane, of a rising-and-falling frame, a spindle journaled in said frame, a pair of bent fingers carried on the end of said spindle and adapted to be carried beneath the article to be lifted by the rotation of said spindle and means controlled at will for rotating said spindle, substantially as described.

15. In a crane, the combination of a pair of bent fingers adapted to be carried beneath the article to be lifted and a spindle carrying said fingers by which they are simultaneously rotated, said spindle being capable of a vertically-sliding movement, substantially as described.

16. In a traveling crane, the combination of a series of carrier-frames, means for simultaneously moving said frames, a lifting mechanism supported by said carrier-frames and comprising a series of lifting-fingers arranged in a line over the article to be lifted and means for determining the position of the article to be lifted beneath said fingers, substantially as described.

17. The combination with a series of overhead tracks, a series of carrier-frames moving thereon, a series of lifting-fingers supported by said carrier-frames, means for positioning the article to be lifted and a series of pockets

arranged beneath said tracks, substantially as described.

18. In a traveling crane, the combination of means for supporting the article to be lifted, 5 a series of pockets for receiving the lifted articles, a series of overhead tracks spanning said support and said pockets, rigid depending frames adapted to run on said tracks, rigid bars for uniting said rigid frames, a lift-

ing mechanism supported by said uniting bars, and means for moving said depending frames along said tracks, substantially as described.
